UNITED STATES PATENT OFFICE.

JOHN H. McDANIEL, OF ST. LOUIS, MISSOURI.

DESIGN FOR A CLOCK CASE.

Application filed February 26, 1923. Serial No. 5,258. Term of patent 3½ years.

To all whom it may concern:

Be it known that I, JOHN H. McDANIEL, a citizen of the United States, residing at St. Louis, in the State of Missouri, have invented a new, original, and ornamental Design for Clock Cases, of which the following is a specification, reference being had to the accompanying drawing, forming a part thereof.

I claim:

The ornamental design for a clock case, as shown.

JOHN H. McDANIEL.
